UNITED STATES PATENT OFFICE.

CHARLES EDWARD HAVILAND, OF LIMOGES, FRANCE.

DESIGN FOR A CUP.

SPECIFICATION forming part of Design No. 22,201, dated February 7, 1893.

Application filed January 13, 1893. Serial No. 458,298. Term of patent 14 years.

To all whom it may concern:

Be it known that I, CHARLES EDWARD HAVILAND, a citizen of the United States, residing at the city of Limoges, in the Republic of France, have invented and produced a new and original Design for a Cup or other Article, of which the following is a specification, reference being had to the accompanying drawings, forming part thereof, and in which—

10 Figure 1 is a perspective view of a cup bearing my design, and Fig. 2 is a horizontal section of same on the dotted line 2—2 of Fig. 1.

15 The leading feature of my design consists of the shape of the body of the cup, as illustrated in the drawings, without regard to the particular form of the handle A which forms no absolutely essential part of either the cup or the design.

The upper and lower edges of the cup are circular in outline, and between these edges 20 the body of the cup consists of the larger and smaller alternating scalloped sections B, which disappear along the upper and lower edges of the cup into the plain surface thereof and have their wider portions along the upper part 25 of the body of the cup.

What I claim is:

The design for a cup or other article, substantially as shown and described.

Signed at the city of Limoges, in the Republic of France, this 27th day of December, 1892.

CHARLES EDWARD HAVILAND.
